CLAIM

The ornamental design for a faucet, as shown and described.

DESCRIPTION

FIG. 1 is a perspective view of a faucet showing our design; FIG. 2 is a front elevational view; FIG. 3 is a rear elevational view; FIG. 4 is a side elevational view; FIG. 5 is a side elevational view; FIG. 6 is a top plan view; and, FIG. 7 is a bottom plan view; and, FIG. 8 is an enlarged view of a portion of FIG. 2 to show detail.

The broken-line disclosures in the drawings represent portions of a faucet that form no part of the claimed design.
